COMBINED HIGH FIDELITY AND STEREO SPEAKER UNIT

Richard H. H. Spencer, Toronto, Ontario, Canada, as-
signor to Clairtone Sound Corporation Limited, Rex-
dale, Ontario, Canada

Filed Apr. 13, 1964, Ser. No. 79,449

Term of patent 14 years

(Cl. D56—4)

FIG. 1 is a front elevational view of a combined high fidelity and stereo speaker unit embodying my new design; FIG. 2 is a right side elevational view; FIG. 3 is a bottom plan view;

FIG. 4 is a top plan view with the slidable tamboured top in an open position; and

FIG. 5 is a top plan view with the slidable tamboured top in a closed position.

The ends of the cabinet portion are substantially flat and unornamented and the rear is the same in appearance as the front shown in FIG. 1.

The broken line showing of high fidelity components in FIG. 4 is for illustrative purposes only.

I claim:

The ornamental design for a combined high fidelity and stereo speaker unit, as shown and described.
